UNITED STATES PATENT OFFICE.

CLARENCE A. MICHEL, OF CLEVELAND, OHIO, ASSIGNOR TO THE GUIDE MOTOR LAMP MFG. COMPANY, OF CLEVELAND, OHIO, A CORPORATION OF OHIO.

AUTOMOBILE HEADLIGHT.

Application filed February 9, 1925. Serial No. 7,794.

This invention relates particularly to automobile head lights and more particularly to a head light embodying a modified form of reflector, a lamp with two filaments and a modified form of lens.

In automobile head light illumination the prime object is to control the beam so as to keep the same within the legal limits and at the same time provide a sufficient road illumination in advance of the car.

These prime objects have been accomplished by the modification of the reflector and also by specially constructed lens and sometimes the combined use of the two. In most of these head lights two lamps have been employed, the main one being located in the center of the reflector and the auxiliary one near the top of the reflector the upper lamp being of smaller candle power than the central lamp. The central lamp may be termed the main lamp and is used for road driving whereas the upper lamp is used for city driving or while passing other automobiles.

The object of my invention is to provide a headlight in which one lamp is arranged in the center and is provided with two filaments the main or driving filament being so positioned and the reflector and lens being of such construction that the top of the beam will be projected at the proper height and as far in advance of the automobile as possible and by using the second filament the top of the beam is drawn or projected downwardly so as to eliminate all possibilities of glare while driving in the city or passing automobiles.

There are various modifications of lens and reflector for accomplishing this in connection with a double filament lamp and I have illustrated one embodiment thereof which forms a part of this specification and in which Fig. 1 is a vertical sectional view of a reflector, lens and lamp constructed in accordance with my invention; Fig. 2 is a face view of the reflector; Fig. 3 is a face view of the lens and Fig. 4 is a side view of the lens.

In carrying out the present invention, I employ a lamp A having two filaments B and C, the filament B being mounted substantially on the axis D of the reflector E and possibly a very slight distance below

said axis. The filament C is arranged a short but perceptible distance above the filament B.

The reflector E has its upper half in the form of a parabola. The rear portion of the lower half of the reflector is a parabola. The forward portion of the lower half of the reflector or that portion indicated in full lines between G and H is modified to the extent that it is carried below or outside of the normal curvature of revolution, the normal curvature of revolution being indicated by the dotted lines whereas the actual curvature is indicated by the full lines. This modification insures the downward reflection of rays from either filament. In order to prevent the formation of sharp angles due to the intersection of different curvatures whether modified or normal curvatures of revolution, and also to facilitate the fabrication of the reflector in one piece I provide transition surfaces between the upper and lower halves of the reflector, the line I' indicating the lower edge of such transition surface, the upper edge of course being the meeting point of the upper and lower half of the reflector which is in the same plane with the axis of the reflector. In connection with this form of reflector and double filament lamp arranged as herein shown and described I preferably employ a lens K having flutes L covering the greater portion of the surface and flutes M at the extreme upper end of the lens, these flutes M being prismatic and thickest at their lower ends so that any rays of light which might be directed upwardly from the forward portion of the upper half of the reflector will be refracted downwardly.

With a lamp constructed as herein set forth the lower filament B is the main or driving filament and when lighted will project the beam of light a considerable distance in advance of the automobile but all of the rays of said beam will be either horizontal or slightly below the horizontal. When, however, the lower filament is extinguished and the upper filament lighted there will be a perceptible bending down of the rays due to the change in position of the filament coupled with the curvatures of the reflecting surfaces of the reflector.

This form of reflector and double filament

lamp gives a limited lateral distribution of the beam of light and the prismatic portion in addition to giving a limited amount of lateral distribution also causes a still further bending down of the rays of light which pass through the upper portion of the lens.

Having thus described my invention, what I claim is:

1. In a light projector, the combination 10 with a reflector, of a lamp having two independently lighted filaments, one of said filaments being slightly below the axis of the reflector and the other one slightly above said axis, the upper half of the reflector being in 15 the form of a parabola, the rear portion of the lower half of reflector being also a parabola, the forward portion of the lower half being carried below and outside the normal curvature of revolution whereby the rays of 20 light from either filament will be directed downwardly, and transition surfaces arranged between the upper and lower halves of the reflector.
2. In a light projector, the combination 25 with a reflector, of a lamp having two inde-

pendently lighted filaments, one of said filaments being slightly below the axis of the reflector and the other one slightly above said axis, the upper half of the reflector being in the form of a parabola, the rear portion of the lower half of reflector being also a parabola, the forward portion of the lower half being carried below and outside the normal curvature of revolution whereby the rays of light from either filament will be directed downwardly, transition surfaces arranged between the upper and lower halves of the reflector, and a lens arranged in advance of said reflector, the major portion of said lens having flutes for causing lateral 40 distribution of light, the extreme upper portion of said lens having flutes, said upper flutes being prismatic and thickest at their lower ends whereby rays of light reflected from the forward portion of the upper half 45 of reflector are refracted downwardly.

In testimony whereof, I hereunto affix my signature.

CLARENCE A. MICHEL.
